Patented Dec. 24, 1974

233,991

ELECTRICAL CONNECTOR

Henry Oliver John Smith, 23 Howland St., London, W1P
6 HQ, England, and Edward Arnold Summerfield, 7
Broadmead, Close Hatch End, Pinner, Middlesex, Eng-
land

Filed Sept. 25, 1972, Ser. No. 291,549

Claims priority, application Great Britain Mar. 30, 1972

Term of patent 14 years

Int. Cl. D13—03

U.S. Cl. D26—1 A

FIG. 1.

FIG. 2.

FIG. 3.

FIG. 4

FIG. 5.

FIG. 6.

FIG. 1 is a top perspective view of an electrical connector showing our new design;

FIG. 2 is a bottom perspective view with a movable part thereof shown in an alternate position;

FIG. 3 is an end elevational view thereof;

FIG. 4 is a side elevational view thereof;

FIG. 5 is a side elevational view thereof, with the movable part in the position shown in FIG. 2; and

FIG. 6 is an end elevational view thereof opposite to that shown in FIG. 3.

We claim:

The ornamental design for an electrical connector, as shown.
